(57) **CLAIM**

The ornamental design for an eyewear viewing device, as shown and described.

DESCRIPTION

FIG. 1 is a perspective view of the eyewear viewing device embodying the present design.

FIG. 2 is a front view of the eyewear viewing device.

FIG. 3 is a rear view of the eyewear viewing device.

FIG. 4 is a top view of the eyewear viewing device.

FIG. 5 is a bottom view of the eyewear viewing device.

FIG. 6 is a left side view of the eyewear viewing device; and,

FIG. 7 is a right side view of the eyewear viewing device.

The broken lines illustrate unclaimed portions of the eyewear viewing device and form no part of the claimed design.
